CORPORATION OF NEW YORK.

BUTTON-SEWING MACHINE.

Application filed April 27, 1922. Serial No. 557,011.

This invention relates to an improvement in button sewing machines, wherein provision is made for a materially strengthened thread anchor in the material through the stitching 5 of the button to the fabric on lines passing through each hole in the button and diverging therefrom to relatively spaced points in the fabric.

The improvement is particularly designed 10 for adapting button sewing machines for the application of two hole buttons to the fabric, under which conditions a series of stitches in the form of loops of thread are passed through the respective button holes 15 successively, the button holder or clamp being operated to register the holes in the button alternately with the needle for successive stitches. For the purpose of the present invention, the material to which the button is 20 to be attached is movable with the button for the successive needle movements, and is also adapted for a periodic movement independent of the button in a direction transverse to the line joining the holes in the button. 25 Thus the button and material move together until the needle has made, say, one-half the number of stitches required to attach the button, whereupon the material is given a movement independent of the button and 30 laterally of the movement of the button and material so as to arrange a portion of the material, different from that through which the previous stitches have passed, in line with the holes in the button. The button 35 and material then move together to present each of the pair of holes in the button alternately to the needle, whereupon the remainder of the needle stitches or loops are passed through the material at points spaced from 40 those points in the material through which the first half of the stitches passed. As a result of this, the button with two holes therein, is secured to the material by stitching loops at four spaced points, thus providing the strengthened anchorage.

From the above general statement, it will be apparent that the button and material move together to successively present the holes in the button in the needle path, and 45 that after a predetermined period, say, one-half the stitching operation, the cloth is given an independent movement, which alines a different portion thereof with the button

holes in the button, so that the subsequent 55 stitches through these button holes, which are made in the usual manner, pass through the material at points spaced from the previous points.

The invention is designed for an additional 60 and important result to overcome an objection heretofore incident to button sewing machines. The initial thread carried through the button and material is generally brought back by the needle upwardly through the button, and in the final attachment of the button remains as a projecting end which must be removed by hand. This objection is entirely overcome by the present invention as, 65 following the initial or first needle movement through the button and material, the 70 material is given a relative movement with respect to the button, which thus brings the opening in the material through which this initial thread passed out of alinement with the hole in the button. This in effect binds 75 the thread between the material and the plate of the machine, and thus prevents the needle from drawing it back through the material and button in its subsequent stitching movement.

The invention also includes the provision 80 of a button holder or clamp and a material holder or clamp, together with cams or similar controls, through which the clamps move in unison for a definite period to cause a 85 series of stitches to be passed through the holes in the button in succession and through the material, whereupon the control for the material clamp imparts to the latter movement independent of the button clamp to ar- 90 range a different portion of the material beneath the holes in the button, whereupon the controls again operate to move both clamps in unison so that the succeeding stitches pass through the button holes in succession but 95 through points in the material spaced from those points through which the first series of stitches passed. Obviously, these controls can be readily adapted for such change or adjustment that the combined or unison 100 movements of the clamps can be either longitudinally or transversely of the sewing machine, thus applying the button with lines of stitches extending either lengthwise or crosswise the garment on its back face and 105 on the forward face of the button, the inde-

pendent movement of the material being at right angles to the lines of button securing stitches in whichever direction they may be applied.

5 Certain embodiments of the invention are illustrated in the accompanying drawings in which—

Figure 1 is a view in side elevation illustrating a mechanism arranged for stitching 10 two hole buttons with the line of the holes arranged transversely of the machine.

Figure 2 is a perspective view of the same.

Figure 3 is a plan of the same.

15 Figure 4 is a perspective view of the material clamp used in connection with the construction shown in Figure 5.

Figure 5 is a perspective view showing a mechanism arranged for use with two 20 hole buttons when the holes in the buttons are to be arranged lengthwise of the machine.

Figure 6 is a perspective, with the parts separated, of the material clamp used in 25 connection with the construction shown in Figures 1 to 3.

Figures 7 to 16, inclusive, are diagrammatic illustrations of the successive steps in securing a two hole button in position, proportions being distorted for clarity of showing.

Figure 17 illustrates also somewhat diagrammatically the engagement of successively positioned sewing loops on the back face of the material before the stitching operation has been completed.

While a two thread machine might be employed, a single thread machine is illustrated generally at 1. It has the usual needle bar carrying the needle 2, and a looper 3, and as adapted for the purposes of the present invention has a material clamp and also a button holder, both to be more particularly hereinafter described.

45 At 4 is shown a bearing plate pivotally and slidably connected to the machine bed by a headed screw 5 passing through a longitudinal slot 6 in the plate and taking into the machine bed. The material clamp 50 is secured to the forward end of the bearing plate, and is preferably constructed in either of two forms for the reason that in sewing buttons where the holes in the buttons are to be arranged transversely of the machine, 55 the material clamp must have its independent movement longitudinally of the machine, while where the holes in the buttons are to be arranged longitudinally of the machine, the material clamp must have its independent movement transversely of the machine, 60 although a single material clamp capable of both movements is within the scope of this invention.

A material clamp having its independent movement longitudinally of the machine is

shown in Figures 1 to 3 and 6, and comprises a plate 7 removably secured by screws 8, or the like, directly to the forward end of the bearing plate 4. A lower clamp plate 9 is directly and slidably secured on the plate 70 7 by screws 10 passing through slots 11 in clamp plate 9 and taking into plate 7. The forward end of the lower clamp plate 9 is formed with an enlarged opening 12 (Figure 2) for the passage of the needle, and its upper surface is preferably roughened about such opening. An upper clamp plate 13 is rigidly secured to the lower clamp plate by screws 14, the forward end of the upper clamp plate being formed with spaced 75 clamping arms 15. The forward ends of the clamping plates 9 and 13 are so relatively arranged as to cause the forward ends of the arms 15 to press with inherent spring pressure toward the lower clamp plate so as to clamp the work therebetween. A bar 16 is secured to the clamp plate as by the screws 14 and projects laterally, as shown in Figures 2 and 6. To the outer end of this bar is fixed the mechanism for giving 80 independent longitudinal motion to the work and the button as will later appear.

The plate 4 is formed with upstanding ears 39, between which is pivoted on a transverse pivot pin 41 lugs 40 depending from the main bar 42 of a button clamp. The forward end of this button clamp is provided with a head 43 adjustably connected thereto through bolt and slot connections 44, 45, this head having the usual side button engaging jaws 46 and movable rear jaw 47, as is common in this type of machine. A spring 48 is interposed between the rear end of the main bar 42 of the button clamp and the plate 4 of the material clamp, this spring tending to normally hold the button clamp pressed down toward the material clamp. The button clamp may be raised at the will of the operator as by the usual treadle and chain connection, indicated generally at 49, and also usual in this type of machine.

By reason of the connection of the material clamp members 9 and 13 to the plate 4 as hereinbefore described, it is evident that this clamp and the material carried thereby may be moved forwardly and rearwardly longitudinally of the machine independently of the button clamp by which movement different portions of the work may be brought into alignment with the holes in the button. This movement is effected through a bar 35 pivoted at 36 to the bar 16 and at 34 pivoted to an arm 32 fixed to a shaft 29. This shaft 29 may be rocked from beneath the bed plate by a suitable cam at 290 (Figure 1). Adjustment of the amplitude of this motion of the material clamp may be secured by adjusting the pivot point 34, the arm 32 being provided with a plu 120 125 130

rality of perforations 33 in any of which the pivot may be engaged. The bar 35, as shown also, is made in two sections overlapping to an adjustable extent and secured together so as to provide for further adjustment. The button clamp must be held against longitudinal movement when the holes in the button are arranged transversely but must be given a lateral movement together with the material clamp to present the two holes of the button in alternation in the needle path. For the purpose of holding the button clamp against longitudinal motion and permitting such lateral movement, an arm 23 is pivoted to the rear end of the plate 4, this arm having a sleeve 24 at its opposite end journaled on a suitable pin or stub shaft upstanding from the sewing machine bed plate. This sleeve 24 has fixed thereto an arm 25 having a slot 26 therein. Riding in this slot 26 is a pivot bolt 27 slidably adjustable lengthwise of a rock arm 28 also fixed to the shaft 29. By fixing the pivot bolt 27 in axial alignment with the shaft 29, as by means of a thumb nut 30, rocking of this shaft will be ineffective to rock the arm 25 and the pivot point between the arm 23 and the plate 4 will be held stationary. This pivotal connection between the arm 23 and the plate 4 provides a fulcrum about which the plate 4 carrying both the material and button clamps may be swung laterally, the slot 6 being sufficiently wider than the shank of the screw 5 to permit the needed range of swinging motion.

For the purpose of producing this swinging motion a shaft 51 is rotatably supported in the bed plate of the machine at one side of the clamps, and is actuated by a cam at 510 arranged below the bed plate. The upper end of the shaft 51 is provided with an arcuate head 52 formed with an undercut slot 53 in which is slidably mounted the head of a bolt 54. This bolt 54 passes through an arm 55, which at its opposite end is connected to the plate 4 of the material clamp by a pin and slot connection 56. A thumb nut 57 cooperates with the bolt 54 to clamp said bolt in any desired position longitudinally of the slot 53 and thus provides any desired degree of lateral or transverse movement to the combined material and button clamps by the oscillation of the head 52. The cams at 290 and 510 are driven as by worms and worm gears from the main shaft 70 which through meshing gears 71 and 72 actuates the looper 3 and through eccentric and lever connections 73, 74 and 75 actuates the needle bar 76 which carries the needle 2.

When it is desired that the line of holes in the button shall extend toward the edge of the material rather than parallel thereto, the button must be placed in the machine with a line of holes extending longitudinally

of the machine and when this is done a different construction of material clamp and certain different connections and adjustments of the machine are employed. A material clamp for use when this button position is desired is shown detached in Figure 4 and connected for operation in Figure 5. It includes a plate 17 secured to the bearing plate 4 similar to and in place of the plate 7 shown in Figure 6, and also includes the lower and upper clamp plates 18 and 19. The lower clamp plate 18, instead of being rigidly secured to the plate 17, as in the other form of clamp, is pivotally connected thereto, as by a stud 20 rising from plate 17 and seated in an opening in the lower clamp plate 18. An operating arm 21 is pivotally secured to the lower clamp plate 18 as at 22.

With this arrangement of buttons it is necessary to move the button and material clamps simultaneously longitudinally of the machine to present the holes in the button successively in the needle path. This is accomplished by adjusting the pivot 27 in the slot 26 to a point away from axial alignment with the shaft 29, as shown in Figure 5, so that the rocking motion of the arm 28 is transmitted to the arm 25 and thus to the arm 23, it being understood that a cam properly cut to effect rocking of the shaft 29 in proper timed relation will be substituted at 290 for the one used with the form of material clamp shown in Figures 1 to 3 and 6 and heretofore described. A spring 50 is shown as interposed between the rear end of the plate 4 and the machine frame, this acting to press the two clamps forwardly so that an edge cam may be used at 290 to give positive back motions to the clamps in proper timed relation with the sewing mechanism, the spring 50 holding the cam follower against the cam and producing the forward motion of the plate 4 and the clamps carried thereby. The extent of motion of the plate 4 may, of course, be adjusted by adjusting the position of the pivot 27 in the slot 26. With this arrangement of the machine, the bar 35 is removed entirely, as shown in Figure 5, the arm 32 rocking idly as the shaft 29 rocks.

The lateral motion of the material clamp independently of the button clamp to change the portions of the material presented in line with the sewing holes in the button is produced by the rocking of the head 52, a cam suitably cut to produce the proper movements being used at 510 in place of that used in the arrangement shown in Figures 1 to 3 in which it gives the combined lateral motion to the two clamps. As shown in Figure 5 this arcuate head is positioned substantially 180° from its showing in Figures 2 and 3, this being done as a matter of convenience in making connections but is not

essential provided the cams are cut for the position used.

The arm 55 is adjusted to bring its outer end in alinement with the shaft 51 so that 5 the rocking of the head 52 will have no effect to move the plate 4 laterally, but instead will hold it against lateral movement while permitting longitudinal movement thereof through the motion of the arm 23. The arm 10 21 of the material clamp, however, is engaged with the head 52 at one side of this shaft 51 so that rocking of the head will act to swing the material clamp about its pivot 20 with the plate 17, thus to impart 15 lateral movement to its forward end which grasps the material. Connection of the arm 21 to the head may be effected by a bolt 58, the head of which rides in the undercut groove 53 of the head and which is provided 20 at its upper end with a thumb nut by which its position in the groove may be fixed when adjusted to give the desired extent of motion to the material clamp. The arm 21 is shown 25 also as made with a pair of overlapping portions relatively adjustable so that the effective length of this arm may be adjusted.

The operation will first be described in connection with applying a two hole button to the material with the holes in the button arranged longitudinally of the machines. Under these conditions the material clamp shown in Figures 4 and 5 will be used. The bolt 27 will be offset from the shaft 29, so as to give the combined clamps a reciprocating longitudinal movement equal to the space between the holes 59 and 60 in the button 61 of Figure 7. The operating arm 21 of the material clamp will be connected to the oscillating head 52 sufficiently out of line with the shaft 51 to impart the necessary extent of oscillation to the pivoted section of the material clamp to give the desired spacing of the two groups of stitches extending through each hole in the button. In the initial stitch, the needle 2 enters the hole 59 in the button and passes down through the material 62 and through a hole 63 in the needle plate 64. Following the 50 looper movement, the needle returns to above the plane of the button and immediately following this operation the movable section of the material clamp is, through the cam connected to the shaft 51, given a movement laterally, independently of the button clamp, 55 to arrange the hole in the material through which the initial stitch passed out of line with the hole 59 in the button, as shown in Figures 8 to 10. The end of the thread is thus offset from the alined holes 59 in the 60 button and 63 in the plate 64 (Figure 10), causing the material to exert a binding action upon the thread and preventing the end of the thread (m, Figure 17) being drawn up through the hole in the button in a subsequent stitch. Both clamps, through the

action of the lever 25, governed by the cam controlling the rocking of the shaft 29, are then reciprocated so that the needle successively stitches through the two holes in the button and through the material therebeneath, the movable section of the material clamp remaining in the position resulting from the above described single movement of the head 52. 70

In each stitching action after the end of the thread has been caught and held the descent of the needle in its work piercing stroke takes with it a loop of thread through a hole in the button and through the material, this loop being caught by the looper 80 and retained during the succeeding withdrawal movement of the needle in a direction opposite to its piercing stroke. In the single thread machine illustrated, successively formed and positioned loops are caused to engage with each other on the under face of the material in the usual manner to form the usual chain stitch as shown in Figure 17 at n, p and q. Of course if a two thread machine were used, each loop of thread passed through the button and the material would be engaged by the second thread on the under side of the material in the well known manner.

Following a predetermined number of stitches through the holes in the button, the material clamp is swung back to its first position through the oscillation of head 52, the material moving laterally independently of the button so that those portions of the material presented in alinement with the holes in the button when the initial stitch was passed are again alined with the holes in the button, and the holes in the material through which the previous stitches passed after the initial stitch are out of line with the holes in the button, as shown in Figures 14 to 17. For the sake of clarity in Figures 14 to 16 the two sides of a single loop only of the thread are shown, except in Figure 16 where four thread lines representing two loops are shown at one point, though it should be evident that in general several loops will be placed at each point. The combined clamps are then continued in their reciprocatory movement to cause the remaining stitches (r, s, t, u, etc., Figure 17) to be passed through the two holes of the button in succession, but these stitches now pass through the material at points spaced from those in the material through which the previous stitches passed. When the number of stitches desired have been completed, it will be apparent that all of the stitches pass through the holes in the button, and that any desired proportion of these stitches pass through the material at definite points, while the remaining number of stitches pass through the material at points spaced from those points. Thus the two hole button is 120 125 130

secured to the cloth at four distinct separate points of anchorage, as will be clearly apparent from Figures 16 and 17, by loops of thread passed through the holes in the 5 button, one group of loops passed through each hole in the button engaging the material at one point and another group through the same hole in the button engaging the material at a different point.

10 In the use of the machine for applying two hole buttons to the material where the holes in the button are set transversely of the machine, the material clamp shown in Figures 1 to 3 and 6 is connected to the plate 15 4 in place of the clamp of Figures 4 and 5, the bolt 27 is alined with the shaft 29 to prevent movement of the lever 25, the arm 16 is connected to the arm 35 and the arm 35 to the arm 32, and the pivot 54 is offset from 20 the shaft 51. It will be apparent that when thus connected, the stitching operation previously described is carried out in substantially the same manner except that in this instance both clamps are moved transversely 25 together to successively present the holes in the button to the needle, by rocking of the head 52, and at a predetermined time, the material clamp is given a movement longitudinally of the machine independently of 30 the button clamp by a rocking motion of shaft 29 acting through the arm 35, to move the material with respect to the holes in the button to provide the four point anchorage of the threads in the material as indicated 35 in Figures 16 and 17.

The method of sewing the buttons as carried out according to this invention and the attachment of the button as a result of this method are not herein claimed as they form 40 the subject matter of a divisional application Serial Number 721,650 filed June 23, 1924, for Method of sewing on buttons.

Having thus described certain embodiments of this invention, it should be evident 45 to those skilled in the art that various changes and modifications might be made therein without departing from its spirit or scope as defined by the appended claims.

We claim:

50 1. In a button sewing machine, a button holder, a material clamp, and means for creating relative movement between the button holder and material clamp following a predetermined number of stitches through 55 the holes in a button and through material, said relative movement positioning the material to receive the stitches through the same button holes at a distance from the original 60 stitches in the material through said button holes.

2. In a button sewing machine, a button holder, a material clamp, means for moving said button holder and material clamp in unison to permit a plurality of stitches to be made through holes in a button and material,

said stitches passing through the button holes in succession, and means for creating a relative movement between the button holder and material clamp following a predetermined number of such stitches to position an unstitched portion of the material in line with said button holes to receive subsequent stitches through said button holes.

3. In a button sewing machine, a button holder, a material clamp, means for moving said holder and clamp in unison to permit stitches to be made alternately through spaced holes in the button and material, and means for creating a relative movement between the button and material during a stitching interval and at an angle to the direction of unison movement to arrange the stitching points in the material of the previous stitches out of line with the holes in the button.

4. In a button sewing machine having a needle, a holder for a two hole button, a material clamp, means for moving the holder and clamp to position holes in the button beneath the needle alternately to cause stitches to pass through the holes in the button and material, and means whereby the material clamp is shifted with respect to the holder during the stitching operation after a plurality of stitches have been made with said holder and material clamp in the same relative positions, to dispose the previous points of stitch anchorage in the material out of line with the holes in the button.

5. In a button sewing machine having a needle, a button holder, a material clamp, means for moving the holder and clamp in unison to position each of a pair of holes of the button beneath the needle alternately to cause stitches to pass through the holes in the button and material, and means whereby the material clamp alone is shifted transversely with respect to the direction of said unison movement during the stitching operation.

6. In a button sewing machine having a needle, a button holder, a material clamp, means for moving the holder and clamp in unison to cause the needle to pass alternately through each of a pair of holes in the button and through the material, and means for independently moving the material clamp alone in a direction at right angles to the direction of unison movement to thereby position the material in a new relation to the button and without interfering with the subsequent unison movement.

7. In a button sewing machine having stitching mechanism, a holder for a two hole button, a material clamp, means for imparting combined movement to the holder and clamp with relation to said stitching mechanism, and means operative independently of said first mentioned means for moving the material clamp alone at right angles to the

70

80

85

110

115

120

125

direction of said combined movement and for maintaining the material clamp in the position relative to said button holder resulting from such independent movement during succeeding combined movements.

8. In a machine of the class described, means for holding material, a button clamp, sewing instrumentalities including a needle, and means for so relatively moving said button clamp and holding means during the sewing operation as to sew through two holes only in the button and four holes in the material.

9. In a machine of the class described, button-holding means, material-holding means, instrumentalities constructed and arranged to attach a button supported by said button-holding means by fastenings extending through the holes in the button and into material held by said material-holding means, and means for so relatively manipulating said button and material-holding means that a plurality of fastenings extending through each hole in the button engage the material at spaced points.

10. In a machine of the class described comprising means for carrying a perforated member, means for holding material, and means for attaching a perforated member carried by said carrying means to material on said material holder and mechanism for so relatively manipulating said means during the attaching operation that a plurality of fastenings extending through a perforation in said member engage the material at each of spaced points.

11. In a machine of the class described, a button carrier, a material holder, sewing instrumentalities for attaching a button carried by said carrier to material held by said holder by stitches a plurality of which pass through each thread hole of the button, and means for so relatively moving the button and material after a plurality of stitch-forming operations as to cause stitches pass-

ing through the same hole in the button to be spaced apart in the material.

12. In a machine of the class described, a button carrier, a material holder, instrumentalities for fastening a button carried by said carrier to material held by said holder, and means for so relating said carrier, holder and instrumentalities as to cause said instrumentalities to place fastenings extending through two holes in the button through four holes in the material.

13. In a machine of the class described, members comprising a button carrier and a material holder, stitching mechanism for attaching a button on said carrier to material on said holder, and means for so relating said members and mechanism during the stitching operation as to hold the starting end of the stitching thread and thereafter to engage the material by stitches passing through each of the holes of the button to spaced points in the material.

14. In a machine of the class described, a material holder, a button clamp, sewing mechanism, and means for relatively moving said holder, clamp and mechanism to sew through two holes in a button into the material at points spaced in a direction laterally of a line joining the said two holes in the button.

15. In a machine of the class described, sewing mechanism, means for holding work and means for holding a button in operative relation to said mechanism for effecting the sewing of the button to the work, and means acting after a plurality of attaching stitches have been made for moving the work relative to the button and mechanism to cause succeeding stitches engaging the same portion of the button to engage a different portion of the work.

In testimony whereof we affix our signatures.

CHARLES T. A. SIBBALD.
JOHN B. RANSOM.
